UNITED STATES PATENT OFFICE

GUY G. STEVENS, OF GROTON, NEW YORK

DESIGN FOR A DILATOR

Application filed January 11, 1933. Serial No. 46,787. Term of patent 7 years.

To all whom it may concern:

Be it known that I, GUY G. STEVENS, a citizen of the United States, residing at Groton, in the county of Tompkins and the State of New York, have invented a new, original, and ornamental Design for a Dilator, of which the following is a specification, reference being had to the accompanying drawing, forming part thereof, which is a perspective view of said dilator showing my new design.

I claim:

The ornamental design for a dilator, as shown.

In testimony whereof, I have herewith set my hand this 9th day of January, 1933.

GUY G. STEVENS.
